(57) CLAIM

The ornamental design for a funnel for directing concrete into a sonotube, as shown and described.

DESCRIPTION

FIG. 1 is a top plan view of a funnel for directing concrete into a sonotube showing my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a perspective view of my design with environment of stakes, ground and sonotube denoted in dashed lines.

The broken line showing of the stakes, ground and sonotube in FIG. 7 is for illustrative purposes only and forms no part of the claimed design.
